CALCULATING MACHINE

Arthur J. Fettig, Detroit, Mich., assignor to Burroughs Adding Machine Company, Detroit, Mich., a corporation of Michigan

Application August 14, 1936, Serial No. 95,959

9 Claims. (Cl. 235—60)

This invention relates to a calculating machine and it is concerned with an improvement for making such machines more automatic.

An item is indexed on a key set calculating machine by depressing the amount keys. During a cycle of operation of the machine, as for example, a total taking cycle, these keys are ordinarily locked against depression. However, after an operator has depressed the total key and the motor bar for a totaling cycle, he may be ready to index an amount in the machine before the total taking cycle is completed. The present invention, in one of its aspects, is directed to providing a construction for enabling the operator to depress these amount keys prior to completion of the total taking cycle.

Ordinarily, in a key set calculating machine, when an item is indexed by depressing the amount keys, the keys remain latched during the major portion of the cycle of machine operation. During this cycle a differential mechanism, including actuators for the register, moves to differential position under the control of the depressed amount keys. A register is engaged with the actuators at the appropriate time, and, near the end of the cycle, the amount keys are released whereupon they return to normal. It is possible to keep the amount keys depressed through several cycles of machine operation by setting a repeat mechanism either by means of a repeat key or the paper carriage. A total cannot ordinarily be taken with the amount keys depressed because in total taking the actuators must move under the control of the register. If the amount keys were depressed, some or all of the actuators might be arrested by the stops controlled by the depressed keys rather than by the register. In fact, the total key is generally locked when an amount key is depressed.

It is sometimes desirable, however, to enter an amount, to take a total, and to then reprint or reenter the same amount. While this could be done by a second depression of the amount keys, the operation of the machine would be speeded up and the work made easier if the operator were not required to index the item a second time. The present invention is directed to a solution of this problem.

The general object of the invention is to provide an improved automatic calculating machine.

A more particular object is to provide a construction that will enable an operator to index an item in the machine while a total taking cycle is being completed.

Another object is to provide an improved 65 levers being differentially positioned with the ac-

mechanism for enabling a total to be taken from a register while the indexing means remains indexed for an amount that has been entered prior to the total taking operation.

5 Other and more particular objects will appear from the following specification and drawings.

An embodiment of the invention is shown in the accompanying drawings, in which:

Figure 1 is a left side elevation and section of 10 a machine with the invention applied thereto, the parts being shown in normal or inactive position.

Fig. 2 is a perspective view showing portions 15 of two rows of keys with the keys in one column being in normal undepressed condition and those in another column depressed for an item-enter- in operation

Fig. 3 is a detail perspective showing certain 20 of the controlling parts in the position they occupy during a total taking operation.

Fig. 4 is a partial side elevation and section 25 showing the control of the invention by the total-taking control means for the main add-subtract register.

Fig. 5 is a partial side elevation and section 30 showing the automatic repeat mechanism.

The invention is shown applied to a Burroughs high keyboard calculating machine whose construction is so well known that the present description of it will be confined to a general explanation and to the parts more particularly associated with the present invention.

General construction

The machine has a plurality of rows or banks 35 of depressible amount keys 10 (Fig. 1) controlling index stops in the form of wires 11 that are adapted to arrest the descent of actuators 12 according to the digital value of the keys depressed. These parts enable an item to be indexed in the machine, the keys being latched in position after being depressed.

An add-subtract register 15—16, sometimes 40 called a "crossfooter," is provided which can be connected to the actuators to perform addition, subtraction, total and sub-total taking. The machine also has a plurality of multiple registers 17 which may be selectively positioned for cooperation with the actuators. The controls for the add-subtract and for the multiple registers are 45 described more particularly in Pasinski patents, Nos. 1,778,506 and 1,911,768, to which reference may be made for details.

The actuators 12 are carried on the ends of 50 levers 18 pivoted loosely on the shaft 19, said levers being differentially positioned with the ac-

tutors. The rear ends of the levers 18 carry type 20 and, after the levers have been positioned, a printing mechanism, including the hammers 21, is operated to drive the type against paper held around a platen 22.

Columnar printing is provided for by mounting the platen 22 on a traveling paper carriage 23 controlled by a tabulating mechanism 24 which is normally operated during each machine cycle to tabulate the carriage from one column to the other near the end of the cycle.

The paper carriage is employed to automatically condition the machine to perform predetermined functions, and one of the functions that may be thus controlled is that of total or subtotal taking from a multiple register as described in Muller Patent 1,854,216. Briefly, the carriage supports a roll 25 operating on a yoke 26 which transmits movement through the connections 27, 28 and 29 to a total taking lever 30. In predetermined columnar positions of the carriage the lever 30 may be moved or rocked clockwise from the position of Fig. 1 to condition the machine to take a total from one of the registers 17.

The machine may be cycled by hand or by a motor, portions 33 of a motor drive being shown in Fig. 1.

When an amount key is depressed from the full line position to the dot-dash line position of Fig. 2, it rocks a detent 35 clockwise against the tension of a spring 36 which normally maintains the detent and its key in underpressed position. The lower ends of these detents extend through slots 37 in slides 38, of which there is one for each row of keys. When a key is depressed the rocking of its detent 35 moves its slide 38 rearwardly where it is latched by a latch 40 urged counterclockwise by a spring 41. The latched slide 38 thus holds the detent 35 of the depressed key against return to normal and it also locks the undepressed keys of its bank and their detents 35, the slide moving under the lower edges of the detents 35 of the undepressed keys. Near the end of a cycle of machine operation, a restoring ball 42 releases all the latches 40 whereupon the slides 38 return forward to normal under the urge of springs 36 for the detents 35.

In order to be able to give the machine several cycles of operation with the amount keys depressed, provision is made for preventing release of the latches 40 for the slides 38, and this is done by controlling the movement of the restoring ball 42 through the control of the pawl 44 that acts on said ball. The machine may be automatically conditioned for repeat operations by a repeat slide 45 controlled by the carriage through a roll 46, a pivoted yoke 47, and connections 48, 49, as shown in Muller 1,397,774. The automatic repeat mechanism not only controls the release of the keys, but it controls the cycling of the machine. When the paper carriage is provided with repeat rolls, the machine will go through a number of cycles automatically depending upon the number of rolls provided, and the keys will remain depressed.

Enabling a total to be taken while the indexing means remains indexed

In the embodiment of the invention shown, the taking of a total with the indexing means indexed is made possible by temporarily removing the control of the actuators from the indexing means.

Referring to Fig. 1, the detents 35 which are rocked clockwise by depression of the amount

keys are ordinarily connected to the index stop wires 11. But in the present invention, the connection is such that the stop wires may be moved relative to the detents under certain conditions.

Referring to Fig. 3, which may be taken as an illustration of a detent in the units order row of keys, the detent 35 is pivoted on a shaft 50. Pivoted loosely on this shaft is an arm 51 to which the stop wire 11 is connected. The arm 10 51 is urged clockwise by a spring 52 against a stud 53 extending from the detent 35. The spring 52 is strong enough so that, when the detent 35 is rocked clockwise by depression of the key 10, the arm 51 moves with it and pulls 15 the stop wire 11 to indexed position. An arm similar to the arm 51 is provided for each detent 35, the arms for the "units" row of keys being to the left of the detents as viewed in Fig. 2, while those for the "tens" row are to the right 20 as shown in said figure. The arms 51 for the two adjacent rows of keys extend downwardly through slots 60 (Fig. 2) in a slide 61, there being one of these slides for each two rows of keys. The slots 60 are long enough and are normally 25 positioned so that, when an amount key is depressed, the corresponding arm 51 is moved against the rear edge of its slot 60 without, however, moving its slide 61.

The control of the actuators by the amount 30 keys, that is, by the indexing means, is temporarily removed, or disabled, by moving the slides 61 forward. This moves the arms 51 together with their stop wires 11, forward, while the amount keys remain in position. The detents 35 for the keys which have been depressed, are 35 latched by their slides 38. The detents 35 in rows where no keys are depressed are not latched but the stop wires 11 in said rows are already 40 in their normal forward position. Since the slides 38 prevent the detents 35 in rows where keys have been depressed from rocking, movement of arms 51 for the keys of said rows stretches the springs 52, the parts moving to the relative position shown in Fig. 3.

Thus, by moving the slides 61 forward, all the stop wires 11 that may have been indexed by depression of the amount keys, are returned forward to normal where they are out of the paths of the actuators which may then be used for 50 total taking under the control of the register.

In the embodiment shown, the slides 61 are moved forward by the total taking control means. As shown in Figs. 1 and 2, this total taking control means is that for the multiple registers 17. 55 The total taking lever 30 has a stud 62 operating in a slot 63 in one arm of a pivoted bell crank lever 64. The other arm of this lever is connected to an abutment slide 65 slidably mounted at its forward end on a stud 66. The forward end of this slide also carries a stud 67 operating against one arm of a bell crank yoke 68 pivoted on shaft 69. The other arm 70 of this yoke is connected by a link 71 to an arm 72 on a shaft 73 that extends across the machine. The shaft 60 73 has a number of arms 74 fixed to it which 65 extend into slots in their respective slides 61, there being, as previously explained, one of these slides for each two rows of keys. When the total taking lever 30 is moved forward, the bell crank 70 64 is rocked counterclockwise which thrusts the slide 65 forward and rocks the yoke 68—70 counterclockwise to rock shaft 73 counterclockwise to move the slides 61 forward. Thus, as an incident to the conditioning of the machine for 75 total taking, the control of the actuators by the

indexing means is automatically disabled. The total may then be taken, after which the total taking lever 30 moves back to its normal position shown in Fig. 1. When the latter movement occurs the slides 61 move back to normal which causes the arms 51 to move back to their normal position. The amount keys remain depressed, but after the total taking operation they are again in control of the actuators. The machine may then be given a cycle of operation during which the actuators will be differentially positioned in accordance with the depressed amount keys and the item that was indexed prior to total taking may be again printed, and entered in the machine if desired.

It is to be understood that, the interlock between the amount and the total keys is omitted so that the total key may be depressed while the amount keys are depressed.

Completely automatic control

The conditioning of the machine above explained may be had by depressing a repeat key to prevent restoration of the amount keys and by depressing a motor bar for each cycle of machine operation desired. Provision is made, however, for completely automatic operation as follows:

Repeat cycles of operation of the machine are controlled by the repeat slide 45 (Fig. 1) heretofore mentioned so that, when an item is entered prior to total taking, and when the motor bar is depressed, the machine will go through a predetermined number of cycles depending upon the number and location of the repeat rolls on the paper carriage. In the total taking column the total lever 30 is automatically moved to total taking position as described in Muller No. 1,854,216. But, in said patent it is necessary to depress the usual total key shown as T in Fig. 1 of the present case, in order to actually obtain the total. In the present machine depression of this total key is made unnecessary.

The depression of the total key T in taking totals from the registers 17 is not for the purpose of controlling the engagement and disengagement of the registers with the actuators. That control is taken care of by the total lever 30. The total key T is used to release the zero stops 80 (Fig. 2) that prevent descent of the actuators 12. These are all released by said total key T in the standard Burroughs machine. In the present case, however, the slide 65 (Fig. 1) is provided with a stud 81 engaging the end of a lever 82 pivoted at 83. The other end of this lever engages one arm of a pivoted bell crank 84 whose other arm engages a stud 85 on one arm of a bail 86 that extends across the machine in front of the zero stops 80. Said stops 80 have projections 87 (Fig. 2) adapted to be engaged by the bail 86.

The arrangement is such that, when total lever 30 is rocked forward, slide 65 moves forward, lever 82 rocks clockwise, bell crank 84 rocks counterclockwise, and bail 86 rocks clockwise to release the zero stops 80.

This makes it unnecessary for the operator to do anything after he enters the item in the column immediately preceding the total taking column. When he depresses the motor bar in this column, the machine is given a cycle during which the item is entered. Near the end of this cycle, the carriage tabulates automatically to the total taking column where the machine is automatically conditioned to take a total and

where it goes through another cycle automatically and takes a total, the control of the actuators by the amount keys, which remain depressed, being automatically disabled. Near the end of the total taking cycle, the carriage tabulates to the next column where it is given another cycle automatically and where the item is again printed or printed and entered, as the case may be, under the control of the amount keys that remained depressed.

Control by total key of main register

As heretofore described, the invention has been explained in connection with the total lever 30 for the registers 17. It will operate equally as well, however, with other function control keys. As an example, a modified form of construction is shown wherein the invention is associated with the total key T for the main add-subtract register 15-16. In fact, the invention will operate with both total taking controls of the same machine, that is, the lever 30 and the key T.

Referring to Fig. 4, the total key T, when depressed, moves the link 90 downwardly to condition the machine for taking a total from the main register 15-16. This is the usual Burroughs total taking control means and a detailed explanation is unnecessary. The key T is on one end of a total taking bell crank 91 which carries a stud 92 that, when the key is depressed, engages the cam edge 93 of an extension 94 of the yoke 68 (Fig. 2). This yoke controls the previously described link 11, arm 12, shaft 13, arms 14 and slides 61 which, when the parts are moved, moves the stop wires 11 to released position to enable a total to be taken.

Thus, even though the amount keys are depressed, when the total key T is depressed, the stop wires 11 corresponding to the depressed amount keys are moved to their normal released position so that a total may be taken without the actuators being arrested by said stop wires. When the total key is released, the stop wires move back to normal so that they are indexed in positions corresponding to the depressed amount keys and are in position to arrest the actuators during the next cycle of machine operation.

Early operation of amount keys during total taking operations

The invention has been explained in connection with an operation of the machine where the amount keys are depressed to enter an item, the amount keys being held depressed during a total taking operation, after which the same item is again entered or printed under the control of the depressed amount key. The invention also has another use.

If no amount keys are depressed prior to a total taking operation, nevertheless, a rapid operator may depress the amount keys to enter an item without awaiting the completion of the total taking cycle. This speeds up the operations on the machine.

As already explained, when the total lever 30 is moved to total taking position, or, when the total key T is depressed, the slides 61 of Fig. 2 are moved forward. Since no amount keys have been depressed, the slides do not move any of the stop wires 11 because such wires are already in their forward positions, but said slides move forward so that the rear edges of slots 60 are against arms 51. The stop wires are thus held forward. The total key, or the total lever 30,

as the case may be, is locked in total taking position during the total taking operation and, thus, the slides 61 are held in their forward positions during such operation. If, while the slides 61 are held forward, some of the amount keys are depressed, the corresponding detents 35 will be rocked clockwise (Fig. 2) and such detents will be latched in position by their respective latch plates 38. Movement of the detents 35 does not affect the stop wires 11, because the arms 14 hold the slides 61 forward and these slides hold arms 51 forward, the rear edges of slots 60 being against arms 51, as just explained. The rocking of the detents 35 merely stretches the springs 52 (Fig. 3) between said detents and their respective arms 51. The amount entered on the keys is thus potentially indexed in the machine.

In order for the amount keys to be depressible during a machine operation, the interlock that prevents depression of said keys during a cycle of operation, as shown in Vincent 890,945, is omitted. The interlock between the amount keys and the total keys has already been omitted as previously explained.

At the end of the total taking operation and when the total key T, or lever 30, is moved back to normal, the slides 61 are allowed to move rearwardly whereupon the springs 52 that have been tensioned by depression of the amount keys act to pull their respective stop wires to indexed position. Thus, the amount that was set up on the keys during the latter part of the total taking operation and potentially indexed in the machine, is completely indexed at the end of the total taking cycle so that the machine can immediately go through another cycle and enter the item that was indexed on the keys. A rapid operator may depress the amount keys while the machine is completing its total taking cycle and, upon such cycle being completed, can depress the motor bar and give the machine another cycle to enter the item.

It should be explained that, although, in normal operations of the machine, the amount keys that have been depressed are automatically released near the end of each machine cycle, the amount keys that may be depressed during a total taking cycle are not released by the machine at the end of such cycle. The release of these keys is effected by the bail 42 (Fig. 5) that is normally rocked forward near the end of the cycle of machine operation to release the latches 40 that release the latch plates 38 (Fig. 1). This bail is rocked by a pass-by pawl 44 mounted on one arm of a three-armed member 101 on the rock shaft 19. The repeat slide 45 has a ledge 106 which, when the slide is in a certain position, blocks the arm 101 so that the pawl 44 will not move down far enough to get behind the stud 107 on the end of the arm 108, that moves bail 42. The repeat slide 45 is controlled by a carriage roll 46 acting through a yoke 47 and connections 48-49 so that when the carriage is in a predetermined position the repeat slide 45 will be moved so that the ledge 106 will block the arm 101 as just explained. The result is that, during the latter part of the cycle, the bail 42 will not be rocked to release the key latches and the keys will be allowed to remain depressed. The machine is thus automatically conditioned so that, even though the amount keys may be depressed during the total taking cycle, such keys will not be released at the end of said cycle, but will remain depressed for the next, or succeeding cycle. The repeat slide 45 normally also controls repeat

machine cycles inasmuch as the arm 108 of the bail 42 is normally, near the end of a machine cycle, moved sufficiently counterclockwise in Fig. 5 to engage the rear end of a slide 109 and move the latter sufficiently forwardly to disengage the usual repeat hook 110 from the stud 111 and thus permit the machine to stop at the end of the cycle. When the slide 45 is so positioned that the ledge 106 prevents the pawl 44 from rocking the arm 108 to release the repeat hook 110, the motor bar remains latched down at the end of the machine cycle and the machine then performs an automatic repeat cycle. When the mechanism herein disclosed is used to permit the operator to enter items on the amount keys during total-taking cycles of the machine, the repeat machine cycle is not wanted because the operator does not want a cycle of machine operation to start until the depression of the amount keys for entry of the item has been completed and, in such use of the invention, the usual repeat hook 110 is accordingly omitted.

I claim:

1. The combination in a calculating machine having means for giving it cycles of operation, actuators, a registering mechanism operable by said actuators in the accumulation of items and controlling said actuators in total taking, total-taking control means, and amount indexing means on said calculating machine normally operating to arrest said actuators in differential positions when the machine is cycled with the indexing means indexed; of means for causing said indexing means, after having been indexed, to remain indexed for a plurality of cycles of machine operation, disabling means operable by said total-taking control means when the latter is conditioned for total taking while said indexing means remains indexed, to disable the control of said actuators by said indexing means to thereby enable said actuators to be controlled by said registering mechanism in a total-taking cycle of operation controlled by said total-taking control means, and means acting, at the end of said total-taking cycle, to return said disabling means to ineffective condition to restore the control of the actuators to said indexing means, whereby, during the cycle of machine operation following said total-taking cycle, and without reindexing said indexing means, the actuators may again be controlled by said indexed indexing means.

2. The combination in a calculating machine having means for giving it cycles of operation, actuators, a registering mechanism operable by said actuators in the accumulation of items and controlling said actuators in total taking, total-taking control means, and amount indexing means on said calculating machine normally operating to arrest said actuators in differential positions when the machine is operated with the indexing means indexed; of means for causing said indexing means, after it has been indexed, to remain indexed for a plurality of cycles of machine operation, disabling means operated by said total-taking control means, when the latter is conditioned for total taking, acting to disable the control of said actuators by said indexing means to enable a total to be taken during which said registering mechanism controls said actuators, and means acting, upon the completion of said total-taking operation, to return said disabling means to ineffective condition to restore the control of said actuators to said indexed indexing means, whereby, after the completion of total taking, and without reindexing said index-

ing means, the machine may be again actuated with the actuators controlled by said indexed indexing means.

3. The combination in a calculating machine having means for giving it cycles of operation, actuators, a register operable by said actuators in the accumulation of items and controlling said actuators in total taking, total-taking control means, depressible amount keys on said machine, and index stops controlled by said amount keys normally operating to arrest said actuators in differential positions when the machine is operated with an amount indexed on said keys; of means for causing the indexed amount keys to remain depressed for a plurality of cycles of machine operation, disabling means operable by said total-taking control means when the latter is conditioned for total taking, while said indexed keys remain depressed, to move the index stops for said depressed keys relative to said keys to thereby disable the control of the actuators by said index stops to enable said actuators to be controlled by said register in a total-taking operation controlled by said total-taking control means, and means acting, at the end of said total-taking operation, to return said disabling means to ineffective condition to restore the control of said actuators to said index stops, whereby, without reindexing said amount keys, the machine may be operated after the total-taking operation with the actuators in the control of the index stops controlled by the indexed amount keys.

4. The combination in a calculating machine having means for giving it cycles of operation, depressible amount keys on said machine upon which items are indexed, index stops controlled by said keys, actuators normally controlled by said index stops when the machine is operated after depression of said keys, a register operable by said actuators in the accumulation of items and controlling said actuators in total taking, and total-taking control means; of means for causing the indexed amount keys, after having been depressed, to remain depressed during a plurality of cycles of machine operation, disabling means operated by said total-taking control means when the latter is conditioned for total taking, acting to move the index stops relative to said indexed keys to thereby disable the control of said actuators by said index stops to enable a total to be taken during which said actuators are controlled by said register, and means acting, upon completion of said total-taking operation, to return said disabling means to ineffective condition to again place said index stops under control of said amount keys, whereby, during a cycle of machine operation following said total-taking cycle and without reindexing said amount keys, the machine may be again actuated with the actuators controlled by the index stops of the indexed amount keys.

5. The combination in a calculating machine having means for giving it cycles of operation, actuators, a registering mechanism operable by said actuators in the accumulation of items and controlling said actuators in total taking, total-taking control means, amount indexing means forming a portion of said calculating machine and normally operating to arrest said actuators in differential positions when the machine is operated with the indexing means indexed, means for retaining said indexing means in indexed condition when indexed, and means normally operat-

ing to disable said retaining means to cause said indexing means to be restored to normal during each machine cycle; of a movable device moved to a new position during the latter part of each machine cycle, means conditioned by said movable device in a predetermined position thereof to disable said restoring means and to cause said cycling means to give the machine an automatic cycle of operation after said movable device moves to its next position, means conditioned by said movable device in said next position of the latter to condition the total-taking control means to cause the mechanism to take a total during said automatic cycle, special means conditioned by said total-taking control means to disable the control of said actuators by said indexing means during said total-taking cycle to thereby enable said actuators to be controlled by said registering mechanism in the total-taking cycle, and means acting, upon completion of said total-taking cycle, to restore said disabling means to ineffective condition to again place the actuators under the control of said indexing means, whereby, during the next cycle, and without reindexing said indexing means, the actuators may again be controlled by said indexed indexing means.

6. The combination in a calculating machine having means for giving it cycles of operation, 30 a movable device moved from one to another of a plurality of positions during successive machine cycles, actuators, a registering mechanism operable by said actuators in the accumulation of items and controlling said actuators in total taking, total-taking control means controlled by said movable device, amount-indexing means on said calculating machine normally operating to arrest said actuators in differential positions when the machine is cycled with the indexing means indexed, means for retaining said indexing means in indexed condition when indexed and restoring means normally operating to disable said retaining means to cause said indexing means to be restored to normal during each machine cycle; of means controlled by said movable device to disable said restoring means to cause said indexing means, after having been indexed, to remain indexed for a plurality of cycles of machine operation, and disabling means conditioned 50 by said movable device while said indexing means remains indexed, to disable the control of said actuators by said indexed indexing means.

7. The combination in a calculating machine having means for giving it cycles of operation, 55 actuators, a registering mechanism operable by said actuators in the accumulation of items and controlling said actuators in total taking, total-taking control means, amount-indexing means on said calculating machine normally operating to arrest said actuators in differential positions when the machine is operated with the indexing means indexed, means for retaining said indexing means in indexed condition when indexed, and restoring means normally operating to disable said retaining means to cause said indexing means to be restored to normal during each machine cycle; of means for disabling said restoring means to cause said indexing means, after it has been indexed, to remain indexed for a plurality of cycles of machine operation, and disabling means operated by said total-taking control means, when the latter is conditioned for total taking while said indexing means remain indexed, acting to disable the control of said actuators by said indexed indexing means.

8. The combination in a calculating machine having means for giving it cycles of operation, registering mechanism, total-taking control means, amount-indexing devices, stop members controlled by said amount-indexing devices, actuators normally controlled by the stop members of set amount-indexing devices in machine operations but controlled by said registering mechanism in total-taking operations, means for retaining said indexing means in set condition when set, and means normally releasing said retaining means for restoring set amount-indexing devices to normal in each cycle of operation of the machine; of repeat means for disabling said releasing means to cause set amount-indexing devices to remain set for a plurality of cycles of operation of the machine, and means controlled by said total-taking control means to cause relative displacement between said actuators and stop members of set amount-indexing devices while the latter devices remain set to thereby disable control of said actuators by said stop members during a total-taking operation with said total-taking control means in total-taking condition and said actuators controlled by said registering mechanism.

9. The combination in a calculating machine having means for giving it cycles of operation, registering mechanism, total-taking control

means, amount-indexing devices, stop members controlled by said amount-indexing devices, actuators normally controlled by the stop members of set amount-indexing devices in machine operations but controlled by said registering mechanism in total-taking operations, means for retaining said indexing means in set condition when set and means normally releasing said retaining means for restoring set amount-indexing devices to normal in each cycle of operation of the machine; of repeat means for disabling said releasing means to cause set amount-indexing devices to remain set for a plurality of cycles of operation of the machine, normally ineffective disabling means controlled by said total-taking control means to cause relative displacement between said actuators and stop members of set amount-indexing devices to thereby disable control of said actuators by said stop members during a total-taking operation with said total-taking control means in total-taking condition and said actuators controlled by said registering mechanism, and means for restoring said disabling means to normal and re-enable control of said actuators by said stop members of said set amount-indexing devices for a following machine operation.

ARTHUR J. FETTIG.
